Samuel Fauer INVENTOR

Albert Macomber BY
ATTORNEY

UNITED STATES PATENT OFFICE.

SAMUEL FAUER, OF NEW YORK, N. Y., ASSIGNOR OF ONE-HALF TO SAMUEL L. WALLERSTEIN, OF NEW YORK, N. Y.

ARTIFICIAL EYE.

1,369,797.

Specification of Letters Patent.

Patented Mar. 1, 1921.

Application filed November 20, 1918. Serial No. 264,819.

To all whom it may concern:

Be it known that I, SAMUEL FAUER, a citizen of the United States, residing in the city of New York, county and State of New York, have made certain new and useful Inventions in Artificial Eyes, and declare the following to be a full and clear description of said invention, reference being had to the accompanying drawings, forming part 10 of this specification.

The object of my invention is to produce an artificial eye for various purposes that will have the appearance of the natural eye and be lifelike; also to have the finished eye 15 less liable to destruction than an eye made entirely of glass, while it may be more cheaply made.

In the drawings—

Figure 1, shows a blank sheet of thin 20 material from which the exposed half of the eye is to be formed up;

Fig. 2, represents a cross section through the center of the front half of an eye containing my invention;

Fig. 3, shows a cross section of a rear half 25 of an eye;

Fig. 4, shows separately the transparent covering used over Fig. 2; and

Fig. 5, shows the two halves and the transparent cover assembled.

In constructing my improved eye I first 30 prepare a thin sheet of metal or other stiff material A, as appears by Fig. 1; I then impress or paint on this blank the pupil a, and outside of that the iris b, together with the other parts of a natural eye surrounding them. These features of the eye are applied to the part A, in any convenient way, but of such coloring matter as will readily lend it 35 self to the bending and forming up into the part B, as hereafter described, without cracking or chipping.

The plate A, is then placed in a suitable forming die and pressed into the shape substantially as shown in Fig. 2.

In this manipulation the pupil a, is preferably depressed to a greater extent than the iris b, and the iris more than the surrounding parts. The pupil has a position at the 40 center of the hemispherical part B, as shown by the section in Fig. 2.

I then prepare a hemispherical shell C, preferably of transparent celluloid which fits snugly over the part B. The transparent shell C, may be slightly extended at 55 its base so as to form a rim c, which is turned in over the base of B. A back piece D, may be used to form the rear half of the eye. Or a flat back may be used if desired. In either case the back is snugly fitted in so 60 as to be surrounded by the lip c, and hold the shell C, in place. If desired the interior of B, may be filled in solid. The colors of the depressed portion of the shell B, which represent the pupil and iris have the best 65 effect when they are sufficiently clear and bright to glisten. In such case the transparent covering C, over the depressed iris and pupil, with its reflective qualities, gives to the article a life like appearance. It will 70 be understood that changes in the means or structures may be employed to obtain these results without departing from the principles of my invention. It is apparent that both the iris and pupil must be depressed 75 below the transparent covering but the amount of their respective depression is not material.

Having described my invention what I claim as new and useful and desire to secure 80 by Letters Patent is—

1. A sheet metal eye, comprising: a metal spherical shell depressed at one pole, the depressed portion being suitably marked to represent the iris and pupil, and the outer 85 spherical surface the eye ball.

2. A sheet metal eye, comprising: a metal spherical shell depressed at one pole, the depressed portion being suitably marked to represent the iris and pupil, and the outer 90 spherical surface the eye ball, and a surrounding transparent covering for said eye.

3. A sheet metal eye, comprising: a metal spherical shell having a spherically formed depression at one pole and a secondary 95 spherically formed depression in said first-named depression, the latter being suitably marked to represent the pupil of the eye, and the former the iris, and the outer spherical portion of said shell the eye ball.

SAMUEL FAUER.
